CLAIM

The ornamental design for a tool grip, as shown and described.

DESCRIPTION

FIG. 1 is a perspective view of a tool grip, showing the new design;

FIG. 2 is a left side view of the tool grip of FIG. 1;

FIG. 3 is a front view of the tool grip of FIG. 1;

FIG. 4 is a back view of the tool grip of FIG. 1;

FIG. 5 is a right side view of the tool grip of FIG. 1;

FIG. 6 is a top view of the tool grip of FIG. 1; and,

FIG. 7 is a bottom view of the tool grip of FIG. 1.

The broken line showing of “tool grip” is included for the purpose of illustrating portions of the article and forms no part of the claimed design.
